UNITED STATES PATENT OFFICE.

MARKUS WALINT, OF ENDICOTT, NEW YORK.

REFRIGERATOR.

Application filed March 13, 1924. Serial No. 699,086.

My invention relates to improvements in refrigerators, and it consists in the combinations, constructions and arrangements herein described and claimed.

5 An object of the invention is to provide a refrigerator having means for utilizing in a highly efficient manner and to a relatively great extent the latent heat of evaporation therewithin so that a relatively low temperature will be maintained in the refrigerator for a relatively long time at a relatively low cost.

10 A further object is to provide a refrigerator constructed in such manner that the melting of a primary refrigerant therein will result in the formation of ice in the refrigerator, such ice then serving as a secondary refrigerant.

15 A further object of the invention is to provide a refrigerator which is thoroughly sanitary and is adapted to be cleaned thoroughly and easily.

20 Other objects and advantages will be apparent from the following description, considered in conjunction with the accompanying drawings, in which—

Figure 1 is a perspective view showing a refrigerator embodying the invention,

25 Figure 2 is a transverse vertical section through the refrigerator.

30 Figure 3 is a horizontal section through the refrigerator, looking substantially along the line 3—3 of Figure 2.

35 Figure 4 is a perspective view of a refrigerant holding tray or receptacle which is comprised in the refrigerator, and

Figure 5 is a perspective view of an inner casing which is comprised in the refrigerator.

40 A refrigerator embodying the invention comprises an outer casing designated generally 1 which includes a body that is substantially rectangular in horizontal sectional contour and is closed at its lower end and open at its upper end. The body of the outer casing may be supported on legs 2 and is provided at its upper end with a hinged lid 3. A relatively large preferably rectangular opening 4 in the front wall of the body of the outer casing normally is closed by a pair of swinging doors 5.

45 An inner box-like casing designated generally 6 also is substantially rectangular in horizontal sectional contour and is adapted to fit within the outer casing 1 and to rest

upon the bottom of the latter. The inner casing 6 preferably is closed at its lower end by a bottom wall 7 and is open at its upper end. An opening 8 in the front wall of the inner casing is substantially in register with the opening 4 in the front wall of the outer casing when the inner casing is disposed within the outer casing. The top, bottom and side walls of a box-like receptacle designated generally 9 extend interiorly 60 of the inner casing 6 from corresponding walls of the opening 8 and are secured to the front wall of the inner casing by any suitable known fastening means, being spaced from the remaining walls of the casing as best seen in Figure 2. The receptacle 9 is closed at its rear by a back wall 10. A horizontal shelf 11 may span the side walls of the receptacle 9 intermediate the height of the latter and may be supported at its 65 ends upon blocks, as at 12, secured to the side walls of the receptacle 9 or in any other suitable known manner.

70 It will be manifest that access may be had to the interior of the receptacle 9 through the openings 4—8 when the doors 5 are open.

75 With the arrangement described, the space within the inner casing extends above the receptacle 9, at the back and at the sides of the receptacle 9 and below the receptacle 9. 80 A vertical partition 13 extends within the inner casing 6 from the upper end of the latter approximately to the level of the top wall of the receptacle 9 and divides the space within the interior of the inner casing above 85 the level of the receptacle 9 into two compartments indicated respectively at 14 and 15. Each of these compartments is open at both its upper and lower ends.

85 The compartment 15 is adapted to receive 90 a vessel 16 adapted to hold a liquid, such as water, the vessel 16 preferably comprising a body and a removable lid. The vessel 16 is removable from the compartment 15 and is supported within the latter by a portion of 95 the top wall of the receptacle 6 so that the upper end of the vessel is approximately level with the upper end of the compartment 15. The body of the vessel 16 is provided with a pivoted bail 17 which may be grasped 100 to effect removal of the vessel 16 from the compartment 15.

105 The compartment 14 is adapted for the reception of a removable tank 18 for holding a refrigerant for cooling the interior of the 110

inner casing 6 and of the parts associated with the latter. The tank 18 is in the form of a box-like structure substantially rectangular in horizontal sectional contour and open at its upper end, being provided at its opposite sides with suspension elements in the form of straps 19 secured to the side walls of the tank 18 and having outturned upper end portions adapted to engage with notches 20 in the upper ends of the front and back walls of the inner casing, whereby the tank 18 will be supported within the compartment 14 with the upper end of the tank 18 adjacent to the level of the upper end of the inner casing 6. The end walls of the tank 18 may be provided with handles 21 adapted to be grasped to effect the convenient removal of the tank from the compartment 14. The tank 18 is divided transversely by a partition 22 to provide a plurality of separate compartments within the tank 18. All of these compartments are open at their upper ends but certain of the compartments, indicated at 23, are provided with drain openings 24 which extend through opposite sides of the tank 18 at the lower ends of the compartments 23. The remaining compartments within the tank 18, indicated at 25, are open only at their upper ends and thus are adapted to hold a liquid. It is to be observed that each of the compartments 25 is flanked by two of the compartments 23. Each of the compartments 25 will be provided with a removable lid or cover, as indicated at 26.

The inner casing 6 and the outer casing 1 are provided with registering openings in corresponding end walls thereof for establishing communication between the lower part of the space within the inner casing and the space exterior of the outer casing. A drain pipe 27 may be removably fitted in these registering openings and may have a faucet or other valve in the outer end thereof, as indicated at 28. Also, the water vessel 16 and the front walls of the inner and outer casings may have registering openings at about the level of the lower end of the vessel 16 for the reception of a removable delivery pipe 29 which will have a valve 30 associated with the outer end thereof. It is to be understood that the drain pipe 27 and the delivery pipe 29 have liquid tight connection with the walls of the openings through which they extend. When the valve 28 is open, water will drain from the lower part of the space within the inner casing 6 through the drain pipe and will be discharged at the outer end of the latter but cannot pass between the drain pipe and the wall of the opening in one end of the inner casing between the inner and outer casings. Likewise, when the faucet 30 is open, water will flow from the vessel 16 through the delivery pipe 29 but water is not permitted to

pass between the delivery pipe 29 and the wall of the opening in the vessel 16 into the interior of the inner casing 6.

The object of making the drain pipe 27 and the delivery pipe 29 removable is that these parts then do not prevent the removal of the inner casing from the outer casing nor of the vessel 16 from the compartment 15 since the drain pipe 27 and delivery pipe 29 may be removed when it is desired to remove the inner casing or the vessel 16 for the purpose of cleaning or for any other cause.

From the foregoing description of the various parts of the device, the operation thereof may be readily understood. The receptacle 9 is adapted for the reception of articles of food or other articles which are to be kept at a relatively low temperature. The vessel 16 is designed to hold a supply of water for drinking purposes. The receptacle 9 may be made of any suitable material which is a good conductor of heat, such as a non-corrosive metal. The vessel 16 likewise may be made of any suitable material, such as glass, galvanized tin or steel or like material. The tank 18 may be made of galvanized tin, steel or other suitable material. Each of the compartments 23 of the tank is designed to hold what may be termed the primary refrigerant and which may consist of alternate layers of crushed ice and a mixture of salt and dry ammonia or like material. Each of the compartments 25 is adapted to hold what may be considered the secondary refrigerant, the same being in the form of water placed in the compartments 25 and being converted into ice as a result of the melting of the primary refrigerant in the compartments 23. Heat is abstracted from the space within the inner casing 6 when the melting of the refrigerant within the compartments 23 of the tank 18 takes place and after ice has been formed in the compartments 25, such ice tends to cool the air within the inner casing. Liquid caused by the melting of the refrigerant within the compartments 23 falls from the drain openings 24 on the walls of the receptacle 9 and aids in cooling the latter. Liquid which accumulates in the lower part of the casing 6 may be permitted to drain therefrom through the drain pipe 27. The primary refrigerant or mixture of crushed ice and dry ammonia or the like may be placed in the compartments 23 at suitable intervals to insure the maintenance of a low temperature within the inner casing and to prevent melting of the secondary refrigerant within the compartments 25. It will also be understood, of course, that if desired, the compartments 25 may be used as receptacles for foodstuffs or the like instead of for the secondary refrigerant above referred to.

The separable parts of the refrigerator may be quickly and thoroughly cleaned and the device therefor is thoroughly sanitary.

Obviously, my invention is susceptible of embodiment in forms other than that illustrated in the accompanying drawings and I therefore consider as my own all such modifications and adaptations of the form of the device herein described as fairly fall within the scope of the appended claims.

I claim:—

1. A refrigerator comprising an outer casing and an inner casing, the walls of said casings being spaced apart, and a receptacle suspended in said inner casing adapted to contain a refrigerant, the walls of said receptacle lying within the walls of said inner casing and spaced therefrom to permit air circulation around said receptacle.

2. A refrigerator comprising an outer cas-

ing and an inner casing, the walls of said casings being spaced apart, a receptacle suspended in said inner casing adapted to contain a refrigerant, storage compartments in said inner casing, said receptacle being spaced from the walls of said inner casing and from said storage compartments to permit air circulation around said receptacle.

3. A refrigerator comprising outer and inner casings, a receptacle suspended in said inner casing and provided with ice compartments, the walls of said receptacle being spaced from said inner casing, storage compartments below said receptacle and spaced therefrom, and drain openings in said ice compartments whereby the drip water therefrom flows down over said storage compartments.

MARKUS WALINT.
